CLAIM

The ornamental design for a tile cutout for animal communications, as shown and described.

DESCRIPTION

FIG. 1 is a perspective view of a tile cutout for animal communications according to my design.

FIG. 2 is a top view thereof;

FIG. 3 is a bottom view thereof; and,

FIG. 4 is a front elevation view thereof, the left, rear, and right side elevations are mirror images.

The broken lines illustrate portions of the tile cutout for animal communications that form no part of the claimed design.

1 Claim, 2 Drawing Sheets
